UNITED STATES PATENT OFFICE

2,545,693

OIL INDICATOR LABEL HOLDER

John R. Grossman, Portland, and William Loren
Milliken, Oregon City, Oreg.

Application November 3, 1947, Serial No. 783,840

1 Claim. (Cl. 40—21)

1

This invention relates generally to internal combustion engines and particularly to an oil indicator.

The main object of this invention is to provide a convenient, inexpensive and positive target for indicating on an oil stick the specific oil being used in the motor in order that the attendant will prevent errors in the servicing of the crank case.

The second object is to construct an oil indicator which will prevent errors in the servicing of a motor and which will insure that the same kind and viscosity of oil are used at all times.

The third object is to so construct the device that changes in oil to be used may be indicated by a simple substitution of the display portion of the indicator.

The fourth object is to produce an indicator of the class described which can be produced at a very low cost and which may be applied to any type of oil stick without interfering with the use thereof.

These and other objects will become more apparent from the specification following as is illustrated in the accompanying drawing, in which:

Fig. 1 is a fragmentary side elevation of an oil stick showing the device attached thereto.

Fig. 2 is a rear elevation of Fig. 1.

Fig. 3 is a front elevation of Fig. 1.

Fig. 4 is an enlarged section taken along the line 4—4 in Fig. 2, showing the device used on a flat stick.

Fig. 5 is a view similar to Fig. 4, but showing the device used on a round stick.

Fig. 6 is a perspective view of the front member taken from the rear side before the lugs are bent inwardly.

Fig. 7 is a plan of the back member.

Fig. 8 is a side elevation of Fig. 7.

Like numbers of reference refer to the same or similar parts throughout the several views.

Referring in detail to the drawing there is shown an oil stick 10 of the flat type, on one end of which is formed a handle 11. The metal washer 12 and felt sealing washer 13 are also indicated. The washer 13 rests on the well 14.

Referring in detail to the invention, same will be seen to consist of two parts, a front 15 and back 16.

The front 15 is circular in form and has a pair of projecting lugs 17 and material is preferably a very ductile metal.

On the front face of the member 15 is an indication 18 of the particular name of the oil.

There is also shown the standard 19 as well as the number 20 indicating the viscosity of the oil according to that standard.

2

Obviously any other information or advertising may be added without departing from the spirit of my invention.

The back 16 is circular in form and has notches 21 formed in the edges adapted to receive the lugs 17 when the parts 15 and 16 are brought into register.

The back 16 is provided with an outwardly curved channel 22 adapted to receive the stick 10 between same and the front 15.

The channel 22 has a central rib 23 extending along the middle thereof adapted to receive the round tube of stick 24 as shown in Fig. 5.

The application of the device merely requires the selection of a front 15 having the desired information and placing it against the stick 10 and then placing a back 16 against it and bending the lugs 17 over against the back 16 where it remains in position until removed by again bending the lugs 17 to the position shown in Fig. 6.

It can be seen from the foregoing that the attendant is constantly kept informed as to the kind of oil that is to be put into the motor.

Obviously other means may be employed for fastening the indicator on the stick and the indicator itself may vary in shape without departing from the spirit of the invention.

What we regard as new and desire to protect is an attachment for oil sticks, whereby the kind and viscosity of the oil being used in a motor are forcibly brought to the notice of the attendant.

We claim:

An oil indicator for use on dip sticks of internal combustion engines comprising a pair of metallic disks of equal diameter, one of said disks having a flat channel formed across the diameter thereof adapted to slidably receive a flat dip stick equaling in thickness approximately the depth of the channel, said channel having a rounded groove formed along the length of the bottom thereof, whose curvature and depth from the outer face of the channelled disk approximates the diameter of a round dip stick, making said round stick slidable therein, the channelled disk having notches formed in opposite edges thereof in a line normal to said channel, the other disk being flat and having lugs projecting from its rim registering with said notches adapted to be bent around the back of said channelled disk and hold the two disks together in concentric relationship, the outside of said flat disk having a marking surface thereon for the entry of mileage travelled and the viscosity of oil used.

JOHN R. GROSSMAN.
WILLIAM LOREN MILLIKEN.
